CONVERSION AND COKING OF HYDRO-CARBON OILS

Jacque C. Morrell, Chicago, Ill., assignor to Universal Oil Products Company, Chicago, Ill., a corporation of Delaware

Application October 13, 1934, Serial No. 748,179
Renewed February 4, 1936

4 Claims. (Cl. 196—49)

This invention particularly refers to an improved process for the fractional distillation of hydrocarbon oils of relatively wide boiling range, such as crude petroleum, for example, accompanied by the selective conversion of relatively low boiling and high boiling fractions of the charging stock as well as selective conversion of relatively low boiling and high boiling intermediate conversion products of the process and also accompanied by reduction of the residual liquid conversion products of the process to substantially dry coke, assisted by the use of highly heated products resulting from conversion of the relatively low boiling fractions of the charging stock and of the intermediate conversion products as a heat carrying medium for the coking operation.

As a special feature of the invention, the overhead vaporous products resulting from the fractional distillation of the charging stock are preferably subjected, either alone or together with selected low boiling insufficiently converted intermediate products of the cracking operation, to conversion or reforming in a heating coil at relatively high temperature and preferably the overhead products from the distilling operation are supplied to this heating coil while still in vaporous state without being first subjected to condensation, which condensation would result in considerable loss of heat, and, in order to obviate the use of a vapor pump for passing the hot vaporous products from the distilling operation through said heating coil, said fractional distillation of the charging stock is preferably accomplished at a pressure sufficiently higher than that employed in the heating coil to overcome the drop in pressure due to friction through the heating coil and succeeding portions of the equipment.

As another feature of the invention, selected high-boiling fractions of the charging stock, comprising, for example, the bottoms from the fractional distilling operation, are preferably subjected to conversion without being passed through a cracking coil. This is accomplished by supplying said high-boiling fractions from the fractional distilling stage of the process directly to the reaction chamber wherein they commingle with the highly heated products resulting from the conversion of intermediate conversion products of the process and are subjected to continued conversion therewith. This method of operation obviates the difficulties often encountered, due to excessive conversion and coking in the heating coil, when high boiling oils, such as bottoms resulting from the fractional distillation of crude petroleum containing relatively heavy materials

of a high coke-forming nature, are supplied to said heating coil for conversion.

As another special feature of the present invention, regulated quantities of the highly heated products from the cracking coil to which the relatively low boiling fractions of the charging stock and, when desired, of the intermediate conversion products of the process are supplied for conversion are utilized as a heat carrying medium to assist reduction of the residual liquid conversion products of the process to coke by introducing the same into direct contact with the materials undergoing coking in the coking zone.

In the present invention all of the above features are accomplished in a unified system of simple form and all of the various features are cooperative and mutually contribute to produce the desired final results.

In one specific embodiment, the invention comprises subjecting hydrocarbon oil charging stock of relatively wide boiling range to fractional distillation at substantial superatmospheric pressure whereby it is separated into relatively low boiling fractions, comprising the overhead vaporous products, and relatively high boiling fractions, comprising condensate or bottoms from the distilling operation, introducing said relatively high boiling fractions into an enlarged reaction chamber also maintained at substantial superatmospheric pressure wherein they commingle with the highly heated products supplied to this zone from a cracking coil of the system, as will be later more fully described, and are subjected to conversion therewith, withdrawing vaporous and liquid conversion products from the reaction chamber and subjecting the latter to coking in a coking chamber operated at substantially reduced pressure, subjecting said low boiling vaporous fractions of the charging stock from the distilling operation to conversion conditions of elevated temperature and superatmospheric pressure in a heating coil, introducing the highly heated products from the heating coil into direct contact with the materials undergoing coking in the coking chamber whereby to assist the coking operation, subjecting the total vaporous conversion products of the process to fractionation, whereby their insufficiently converted components are condensed as reflux condensate and separated into selected relatively low boiling and high boiling fractions, subjecting fractionated vapors of the desired end boiling point to condensation, collecting and separating the resulting distillate and gas, subjecting said relatively low boiling fractions of the reflux condensate to fur-

ther conversion in the same heating coil to which said low boiling vaporous fractions of the charging stock are supplied, subjecting said relatively high boiling fractions of the reflux condensate to independently controlled conversion conditions of elevated temperature and superatmospheric pressure in a separate heating coil and introducing the stream of highly heated products from said separate heating coil into the reaction chamber to commingle with and effect conversion of said high boiling fractions of the charging stock.

The accompanying diagrammatic drawing illustrates one specific form of apparatus in which the process of the invention may be accomplished.

Referring to the drawing, hydrocarbon oil charging stock for the process, preferably comprising an oil of relatively wide boiling range containing an appreciable quantity of both relatively low boiling and relatively high boiling components, is supplied through line 1 and valve 2 to pump 3 by means of which it is fed through line 4 and, in the case here illustrated, is supplied through valve 5 to heating coil 6, wherein it is heated by means of heat supplied from a furnace 7 of any suitable form, preferably at a substantial superatmospheric pressure, to a temperature sufficient to effect its subsequent fractional distillation in column 10, to which it is supplied from heating coil 6 through line 8 and valve 9.

Distilling column 10 is preferably operated at a substantially superatmospheric pressure in order to eliminate pumping of the overhead vaporous products from this zone supplied to cracking coil 13. In the case here illustrated, the charging stock is separated by fractional distillation in column 10 into a selected overhead vaporous product of the desired end boiling point and bottoms, which latter comprise components of the charging stock remaining unvaporized in column 10 as well as the components which are condensed in this zone as reflux condensate. It is, of course, also within the scope of the invention, particularly in case the charging stock contains any desirable low boiling, intermediate or high boiling fractions which it is not desired to subject to conversion, to separate the charging stock into more than two selected fractions and to withdraw said desirable components such as, for example, straight-run gasoline of good anti-knock value, lubricating oil, asphaltic material, etcetera, from the system by well known means (not shown).

The selected low boiling components of the charging stock remaining uncondensed in column 10 are withdrawn, in the case here illustrated, from the upper portion of this zone through line 11 to be supplied therefrom through valve 12 to conversion or reforming in heating coil 13.

When desired, a regulated portion of the overhead vaporous product from column 10 may be subjected to condensation, by well known means (not shown), for the purpose of forming distillate which may be utilized as a refluxing medium in column 10 by recirculating said distillate to the upper portion of this zone, by well known means (not shown). This is only one of the many well known satisfactory methods which may be employed for assisting fractionation in column 10 and maintaining the desired vapor outlet temperature from this zone so as to control the end boiling point of the materials subjected to conversion in heating coil 13.

In the case here illustrated the high boiling fractions of the charging stock, comprising the bottoms from the fractional distilling operation, are withdrawn from the lower portion of column

10 through line 17 and valve 18 to pump 19 by means of which they are fed through line 20 and valve 21 and are introduced into reaction chamber 22, to commingle therein with the highly heated products from heating coil 41, which are supplied to this zone as will be later more fully described, whereby said high boiling fractions of the charging stock are heated to a relatively mild conversion temperature and subjected in reaction chamber 22 to conversion, together with the products from heating coil 41. Pump 19 may, of course, be by-passed by well known means (not shown), when a sufficient pressure is employed in column 10 to obviate the use of a pump for supplying oil therefrom to reaction chamber 22.

Both vaporous and liquid conversion products are withdrawn, in the particular case here illustrated, from the lower portion of chamber 22 through line 23 and valve 24 and are introduced into coking chamber 25. It is, of course, also within the scope of the invention to separately withdraw all or a regulated portion of the vaporous conversion products from chamber 22 at any desired point in this zone above the point of removal of the liquid conversion products, in which case the vaporous products so withdrawn may be separately supplied to coking chamber 25 or to fractionator 30 or in part to both, as desired. In case a regulated portion or all of the vaporous conversion products from chamber 22 are withdrawn from this zone separate from the residual liquid it is within the scope of the present invention to partially cool the same, particularly in case they are supplied to fractionator 30. This cooling may be accomplished by means of a heat exchanger or in any other suitable manner and the heat recovered may be utilized, for example, to preheat the charging stock and effect or assist its fractional distillation, although well known means whereby this particular method of operation may be accomplished are not shown in the drawing.

Coking chamber 25 is preferably operated at a substantially reduced pressure relative to that employed in reaction chamber 22 although a substantial superatmospheric pressure may be employed in the coking chamber and, when desired, the pressure in the coking zone may be substantially the same or even higher than that employed in the reaction chamber, in which case a pump of any suitable well known form (not shown) is preferably employed in line 23 for transferring the residual liquid from chamber 25. Although only a single coking chamber is shown in the drawing two or more such zones may be employed, when desired, to give additional space for the deposition of coke and they may be either simultaneously operated or, preferably, are alternately operated, cleaned and prepared for further operation in order that the coking stage of the process, in common with the rest of the system, may be operated continuously. The coke formed in chamber 25 is allowed to accumulate within this zone to be removed therefrom, after the operation of the chamber is completed, in any well known manner (not shown). Chamber 25 is provided with a drain-line 26, controlled by valve 27, which may also serve as a means of introducing steam, water or other suitable cooling medium into the chamber after its operation is completed and after it has been isolated from the rest of the system in order to hasten cooling of the chamber and facilitate the removal of coke therefrom.

The vaporous products from coking chamber 25, including the vapors evolved in this zone by the coking operation as well as any vaporous products supplied thereto from other portions 5 of the system, are directed through line 28 and valve 29 to fractionation in fractionator 30, together with any vaporous products which may be supplied to the fractionator from chamber 22 in the manner previously indicated. The insufficiently converted components of the vaporous products supplied to fractionator 30, including 10 their fractions boiling above the range of the desired final light distillate product of the process, as well as, when desired, regulated quantities of 15 any selected high boiling components of the desired light distillate product which are of inferior anti-knock value, are condensed in this zone as reflux condensate and preferably, as in the case here illustrated, are separated into 20 selected relatively low boiling and high boiling fractions.

The selected low boiling fractions of the reflux condensate formed in fractionator 30 may be withdrawn from any suitable intermediate point 25 or plurality of points in this zone, for example, through line 31 and valve 32, to pump 33 by means of which they are fed through line 34 and valve 35 into line 11, to commingle therein with the low boiling vaporous fractions of the charging 30 stock from column 10 and be subjected to conversion therewith in heating coil 13. When desired, the low-boiling fractions of the reflux condensate may be preheated, in any well known manner (not shown), prior to their introduction 35 into heating coil 13 and may thereby be supplied to this zone in vaporous state, in common with the low boiling fractions of the charging stock.

Heating coil 13 is located within a furnace 14 of any suitable form which furnishes the heat 40 required to subject the oils supplied to this zone to the desired relatively high conversion temperature, preferably at a substantial superatmospheric pressure, and the stream of highly heated conversion products are discharged from this 45 zone through line 15 and valve 16 into coking chamber 25 wherein they come into direct contact with the materials undergoing coking in this zone and furnish heat for the coking operation. It is, of course, also within the scope of the present invention, although not illustrated in the 50 drawing, to supply only a regulated portion of the stream of highly heated products from heating coil 13 to chamber 25, in which case the remainder may be directed, by well known means 55 (not shown), to reaction chamber 22. It is also within the scope of the invention, although only one point of introduction is illustrated, to supply heated products from chamber 13 to chamber 25 at any desired point or plurality of points in this 60 zone.

The relatively high boiling fractions of the reflux condensate formed in fractionator 30, or the total reflux condensate, in case no separation of low boiling and high boiling fractions is effected, 65 may be withdrawn from the lower portion of fractionator 30 through line 36 and valve 37 to pump 38 by means of which this material is supplied through line 39 and valve 40 to conversion in heating coil 41.

70 Heating coil 41 is located in a furnace 42 of any suitable form capable of furnishing the required heat to the oil passing through the heating coil to bring it to the desired conversion temperature, preferably at a substantial superatmospheric 75 pressure, and the stream of heated products from

heating coil 41 is directed through line 43 and valve 44 into reaction chamber 22, to commingle therein with the high boiling fractions of the charging stock supplied to this zone, as previously described.

Chamber 22 is preferably maintained at a substantial superatmospheric pressure, which may be substantially the same or somewhat lower than that employed at the outlet from heating coil 41, and, although not illustrated in the drawing, 10 chamber 22 is preferably insulated against the excessive loss of heat so that continued conversion of the products from heating coil 41 and conversion of the high boiling fractions of the charging stock supplied to this zone may be 15 accomplished therein.

Fractionated vapors of the desired end boiling point, preferably comprising materials within the boiling range of motor fuel and of good anti-knock characteristics, are withdrawn, together 20 with uncondensable gas produced by the process, from the upper portion of fractionator 30 through line 45 and valve 46 and are subjected to condensation and cooling in condenser 47. The resulting distillate and gas passes through line 48 25 and valve 49 to collection and separation in receiver 50. Uncondensable gas may be released from the receiver through line 51 and valve 52. Distillate is withdrawn from receiver 50 through line 53 and valve 54 to storage or to any desired 30 further treatment. When desired, a regulated portion of the distillate collected in receiver 50 may be recirculated by well known means (not shown) to the upper portion of fractionator 30 35 to assist fractionation of the vapors in this zone and to maintain the desired vapor outlet temperature from the fractionator.

In a process of the character illustrated and above described, the preferred range of operating conditions may be approximately as follows: The 40 temperature to which the charging stock is subjected for the purpose of effecting its fractional distillation may range, for example, from 500 to 800° F., or thereabouts, depending upon its characteristics, the desired separation to be effected 45 and the pressure employed in the fractional distilling stage of the process, which pressure may range, for example, from 100 to 500 pounds, or thereabouts, per square inch. The conversion temperature employed at the outlet from the 50 heating coil to which the total reflux condensate from the fractionator of the system or only the high boiling fractions of the reflux condensate are supplied may range, for example, from 875 to 975° F., preferably with a substantial superatmospheric pressure, measured at the outlet from the heating coil, of from 100 to 500 pounds, or thereabouts, per square inch. Substantially 55 the same or somewhat lower superatmospheric pressure may be employed in the reaction chamber. The heating coil to which the low boiling vaporous fractions of the charging stock from the distilling operation are supplied, either alone or together with selected low boiling fractions of the reflux condensate, may range, for example, 60 from 900 to 1100° F., preferably with a substantial superatmospheric pressure at this point in the system of from 200 to 500 pounds, or more, per square inch although, when desired, lower pressures down to 100 pounds, or less, per square 65 inch may be employed in this zone. The coking zone, as already indicated, is preferably operated at a substantially reduced pressure relative to that employed in the reaction chamber ranging, for example, from 100 pounds, or thereabouts, 70 75

per square inch down to substantially atmospheric pressure although, when desired, higher pressures up to or even higher than that employed in the reaction chamber, but preferably no higher than the pressure employed in heating coil 13, 5 may be utilized in the coking zone. The pressures employed in the fractionating, condensing and collecting portions of the system may be substantially the same or somewhat lower than 10 the pressure employed in the coking zone.

As a specific example of one of the many possible operations of the process of the present invention as it may be accomplished in an apparatus of the character illustrated and above 15 described, utilizing as charging stock a Wyoming crude of about 27° A. P. I. gravity containing less than 5% of material boiling up to 250° F.; the charging stock is heated to a temperature of approximately 750° F. at a superatmospheric pressure of about 200 pounds per square inch. The overhead stream of vaporous products from the distilling operation, which is removed from the distilling column at a temperature of approximately 575° F., is subjected, together with a selected low boiling fraction of the reflux condensate from the fractionator of the system, having a boiling range of approximately 350 to 20 600° F., in a heating coil, to an outlet conversion temperature of approximately 1000° F. with a 25 pressure in this zone substantially equalized with that in the distilling column. The highly heated products from this heating coil are introduced into a coking chamber where they come into contact with the residual liquid withdrawn from the 30 reaction chamber of the system and effect its reduction to coke. The remaining portion of the reflux condensate from the fractionator of the system, comprising its high boiling components, are subjected in a separate heating coil to an outlet 35 conversion temperature of approximately 950° F. at a superatmospheric pressure of about 300 pounds per square inch and the heated products are introduced to the reaction chamber, which is maintained at substantially the same 40 pressure, wherein they commingle with and effect conversion of the high boiling fractions of the charging stock from the distilling operation. This operation will produce, per barrel of charging stock, approximately 60% of 400° F. end-point 45 motor fuel having an anti-knock value equivalent to an octane number of approximately 70, about 65 pounds of low volatile coke and approximately 1250 cubic feet of rich uncon- 50 densable gas.

55 I claim as my invention:

1. In a process for the fractional distillation and pyrolytic conversion of hydrocarbon oils wherein intermediate conversion products of the process are subjected to conversion conditions of 60 elevated temperature and superatmospheric pressure in a heating coil and communicating enlarged reaction chamber, vaporous and residual liquid conversion products withdrawn from the reaction chamber, the latter subjected to coking 65 in a coking chamber, vaporous conversion products of the process, including those from the coking zone, subjected to fractionation, whereby their insufficiently converted components are condensed as reflux condensate, fractionated 70 vapors of the desired end boiling point subjected to condensation, the resulting distillate collected and reflux condensate from the fractionator of the system, comprising said intermediate conversion products of the process, returned to the heating coil for further conversion, the improvement 75

which comprises subjecting hydrocarbon oil charging stock for the process, comprising an oil of relatively wide boiling range, to fractional distillation at substantial superatmospheric pressure whereby it is separated into selected relatively low boiling and high boiling fractions, withdrawing said low boiling fractions from the fractional distilling stage in vaporous state and supplying the same without intentional condensation thereof to a separate heating coil wherein they are subjected to conversion conditions of elevated temperature and superatmospheric pressure, introducing the highly heated products from said separate heating coil into direct contact with the materials undergoing coking in the coking chamber for the purpose of assisting their reduction to coke and supplying said selected high boiling fractions of the charging stock from the fractional distilling stage to the reaction chamber wherein they commingle with and are subjected to conversion together with the products from the first mentioned heating coil. 10 15 20

2. In a process for the fractional distillation and pyrolytic conversion of hydrocarbon oils wherein intermediate conversion products of the process are subjected to conversion conditions of elevated temperature and superatmospheric pressure in a heating coil and communicating enlarged reaction chamber, vaporous and residual liquid conversion products withdrawn from the reaction chamber, the latter subjected to coking in a reduced pressure coking chamber, vaporous conversion products of the process, including those from the coking zone, subjected to fractionation, whereby their insufficiently converted components are condensed as reflux condensate, fractionated vapors of the desired end boiling point subjected to condensation, the resulting distillate collected and reflux condensate from the fractionator of the system, comprising said intermediate conversion products of the process, returned to the heating coil for further conversion, the improvement which comprises subjecting hydrocarbon oil charging stock for the process, comprising an oil of relatively wide boiling range, to fractional distillation whereby it is separated into selected relatively low boiling and high boiling fractions, withdrawing said low boiling fractions from the fractional distilling stage in vaporous state and supplying the same, without intentional condensation thereof, to a separate heating coil wherein they are subjected to pyrolytic conversion, introducing the highly heated products from said separate heating coil into direct contact with the materials undergoing coking in the coking chamber for the purpose of assisting their reduction to coke and supplying said selected high boiling fractions of the charging stock from the fractional distilling stage to the reaction chamber, wherein they commingle with and are subjected to conversion together with the products from the first mentioned heating coil. 30 35 40 45 50 55 60 65 70 75

3. In a process for the fractional distillation and pyrolytic conversion of hydrocarbon oils wherein intermediate conversion products of the process are subjected to conversion conditions of elevated temperature and superatmospheric pressure in a heating coil and communicating enlarged reaction chamber, vaporous and residual liquid conversion products withdrawn from the reaction chamber, the latter subjected to coking in a coking chamber, vaporous conversion products of the process, including those from the coking zone, subjected to fractionation, whereby 75

- their insufficiently converted components are condensed as reflux condensate and separated into selected relatively low boiling and high boiling fractions, fractionated vapors of the desired end boiling point subjected to condensation, the resulting distillate collected and said high boiling fractions of the reflux condensate from the fractionator of the system, comprising said intermediate conversion products of the process, returned to the heating coil for further conversion, the improvement which comprises subjecting hydrocarbon oil charging stock for the process, comprising an oil of relatively wide boiling range, to fractional distillation at substantial superatmospheric pressure whereby it is separated into selected relatively low boiling and high boiling fractions, withdrawing said low boiling fractions from the fractional distilling stage in vaporous state and supplying the same, without intentional condensation thereof, to a separate heating coil wherein they are subjected to conversion conditions of elevated temperature and superatmospheric pressure, returning said selected low boiling fractions of the reflux condensate to said separate heating coil for further conversion, introducing the highly heated products from said separate heating coil into direct contact with the materials undergoing coking in the coking chamber for the purpose of assisting their reduction to coke and supplying said selected high boiling fractions of the charging stock from the fractional distilling stage to the reaction chamber wherein they commingle with and are subjected to conversion together with the products from the first mentioned heating coil.
4. In a process for the fractional distillation and pyrolytic conversion of hydrocarbon oils wherein intermediate conversion products of the process are subjected to conversion conditions of elevated temperature and superatmospheric pressure in a heating coil and communicating en-
- larged reaction chamber, vaporous and residual liquid conversion products withdrawn from the reaction chamber, the latter subjected to coking in a reduced pressure coking chamber, vaporous conversion products of the process, including those from the coking zone, subjected to fractionation, whereby their insufficiently converted components are condensed as reflux condensate and separated into selected relatively low boiling and high boiling fractions, fractionated vapors of the desired end boiling point subjected to condensation, the resulting distillate collected and said high boiling fractions of the reflux condensate from the fractionator of the system, comprising said intermediate conversion products of the process, returned to the heating coil for further conversion, the improvement which comprises subjecting hydrocarbon oil charging stock for the process, comprising an oil of relatively wide boiling range, to fractional distillation whereby it is separated into selected relatively low boiling and high boiling fractions, withdrawing said low boiling fractions from the fractional distilling stage in vaporous state and supplying the same, without intentional condensation thereof to a separate heating coil wherein they are subjected to pyrolytic conversion, returning said selected low boiling fractions of the reflux condensate to said separate heating coil for further conversion, introducing the highly heated products from said separate heating coil into direct contact with the materials undergoing coking in the coking chamber for the purpose of assisting their reduction to coke and supplying said selected high boiling fractions of the charging stock from the fractional distilling stage to the reaction chamber wherein they commingle with and are subjected to conversion together with the products from the first mentioned heating coil.
